(No Model.)

W. J. STEWART.
FEEDING MECHANISM FOR SEWING MACHINES.

No. 596,920.

Patented Jan. 4, 1898.

Attest:

Geo H. Arthur

Inventor:

William J. Stewart.

By Robert P. Ruine

Attorney.

UNITED STATES PATENT OFFICE.

WILLIAM J. STEWART, OF CHICAGO, ILLINOIS.

FEEDING MECHANISM FOR SEWING-MACHINES.

SPECIFICATION forming part of Letters Patent No. 596,920, dated January 4, 1898.

Application filed November 8, 1895. Serial No. 568,338. (No model.)

To all whom it may concern:

Be it known that I, WILLIAM J. STEWART, a citizen of the United States, residing at Chicago, in the county of Cook and State of Illinois,

5 have invented a certain new and useful Improvement in Feeding Mechanism for Sewing-Machines; and I do hereby declare the following to be a full, clear, and exact description of the same, reference being had to the accompanying drawings, forming a part of this specification.

This invention relates to the mechanism for operating the cloth-feeding bar of sewing-machines, and more particularly to that type of 15 such feeding mechanisms in which a gyratory operating shaft or lever is arranged beneath the bed of the machine, with its forward end fulcrumed in a suitable bearing on said bed at a point forward of the feed-bar and with 20 its rear end connected by link connections with an operating-eccentric on the driving-shaft of the machine, so as to receive a gyratory motion therefrom, such gyratory operating shaft or lever having intermediate connections 25 to the sewing-machine feed-bar, so as to impart the requisite forward-and-back, as well as the up-and-down movement to such feed-bar; and the object of the present improvement is to provide a novel, simple, 30 and efficient structural arrangement and combination of the parts of such type of feed mechanisms, whereby the same are rendered very efficient in operation, as well as cheap and durable in construction, all as will hereinafter more fully appear and be more particularly pointed out in the claim. I attain 35 such object by the construction and arrangement of parts illustrated in the accompanying drawings, in which—

40 Figure 1 is a bottom plan of a sewing-machine illustrating my present improvement; Fig. 2, a transverse section at line xx , Fig. 1, illustrating the shuttle and feed-operating eccentric and their connections; Fig. 3, an 45 enlarged detail longitudinal sectional elevation at line $x'x'$, Fig. 1; Fig. 4, an enlarged transverse sectional elevation at line x^2x^2 , Fig. 3.

Similar numerals of reference indicate like 50 parts in the several views.

As represented in the drawings, the general arrangement of the feed-operating mechan-

ism, &c., will be substantially the same as that shown in my former Letters Patent, No. 460,730, dated October 6, 1891, and No. 533,566, 55 dated February 5, 1895.

Referring to such drawings, 1 represents the cloth-feeding bar, which in the construction shown is guided in a slot or groove in the guide-post 2, that projects downwardly from 60 the under surface of the bed 3 of the machine, such feed-bar being fulcrumed by an elongated horizontal slot in its forward end upon a cross-pin 4 of the guide-post 2, so as to have a horizontal reciprocating movement 65 at its forward end, while its rear end is left free to move back and forth, as well as up and down in the operation of the machine.

5 is the gyratory operating shaft or lever, pivoted at a point forward of the feed-bar 1 70 in a pendent post 6 on the under side of the bed of the machine, the rear end of such shaft being free to gyrate.

7 is an operating link connection similar to that shown in my former patent, No. 533,566, 75 the upper end of which is provided with an eccentric-yoke that embraces the operating-eccentric 8 on the driving-shaft 9 of the machine, while the lower end of such link connection is formed with a tubular eye that engages 80 the spherically-formed rear end of the gyratory shaft or operating-lever 5.

10 is an adjustable sliding block adapted to move in a vertical guide-slot 11 in the vertical portion of the machine-arm and be held 85 to its required adjustment by a thumb or set screw 12.

13 is the pivot-link connecting the adjustable block 10 to the operating link connection 7, the connection to the said block 10 being by means of a pivot-pin and to the link 7 by means of a sleeve 14, adapted to slide thereon.

As in my former patent, the circle of gyration of the lower end of the link connection 7 95 in a vertical plane will remain constant regardless of the adjustment of the pivot-link 13, and consequently the up-and-down movement of the feed-bar 1 will remain constant. The gyration of the lower end of the operating link connection 7 in a horizontal plane 100 varies with the adjustment of the pivot-link 13 and its carrying-block 10, increasing as such parts are adjusted upward toward the

operating-eccentric 8 and decreasing as such parts are adjusted downwardly away from the eccentric, and accordingly the forward and backward movements of the cloth-feeding bar 1 can be adjusted to suit any required length of stitch without affecting the constant up-and-down movement of such feeding-bar.

The novelty of present improvement consists in operating the cloth-feeding bar in its forward and backward movements in a direct manner by the engagement of the gyratory operating-shaft 5 in a vertical recess 15 in the said bar and in imparting the up-and-down movement to such cloth-feeding bar through the instrumentality of a headed stud 16, that projects forwardly from the cloth-feeding bar, with its headed portion adapted to bear against the gyratory operating-shaft 5, as shown.

With this improved construction the long movement in a horizontal plane and the comparatively short up-and-down movement in a vertical plane requisite in sewing-machine

feed mechanisms is attained in a very cheap, simple, and effective manner.

Having thus fully described my said invention, what I claim as new, and desire to secure by Letters Patent, is—

A feeding mechanism for sewing-machines, comprising in combination, the cloth-feeding bar 1, fulcrumed to the bed of the machine, and guided thereon, and provided with a vertical recess 15 and a forwardly-projecting stud 16, a gyratory operating-shaft 5, journaled on the bed of the machine at a point forward of the feed-bar, and adapted to engage the recess 15 and stud 16, and means for imparting a gyratory motion to the rear end of the shaft 5, substantially as set forth.

In testimony whereof witness my hand this 10th day of September, 1895.

WILLIAM J. STEWART.

In presence of—

ROBERT BURNS,
JAMES LAVALLIN.
